UNITED STATES PATENT OFFICE.

ALBERT N. CRAMER, OF TOLEDO, OHIO, ASSIGNOR TO THE OWENS BOTTLE COMPANY, OF TOLEDO, OHIO, A CORPORATION OF OHIO.

GLASS-FORMING MACHINE.

Application filed February 25, 1927. Serial No. 170,806.

The present invention relates to improvements in glass forming machines, and more particularly to mold bottom construction. In the type of mold bottom with which this invention is illustrated, said bottom is made up of a plunger section movable longitudinally through an annular section, said sections being shaped to coact with each other to form the bottom of ware in the finishing mold. The plunger section may, for example, be of a shape to form a re-entrant bottom in the bottle which is being produced. The usual practice has been to support said plunger section in its uppermost or operative position, by a continuous cam track whose active face is of such shape that it permits the plunger section to drop down into the annular section of the mold bottom during intervals between the finish blowing operations. Because of the difficulty encountered in accurately forming the face of the plunger supporting cam track, said track is such that it frequently causes the plunger section to move up and down slightly in the annular mold bottom section during blowing of the ware, causing alternate contraction and expansion of portions of the glass forming the bottom of the ware, such condition resulting in the formation of "checks" or rough portions upon the bottoms of the ware being produced.

An object of the present invention is to eliminate the formation of "checks" or rough portions on the ware bottoms by locking the plunger section against the described movement relative to the annular bottom section during blowing of the ware to its final form.

A further object is to provide means operating automatically at proper intervals to unlock the plunger section, thereby permitting the plunger section to drop away from the bottle or other article being blown, just prior to reaching the station at which the article is to be ejected from the forming machine.

Other objects will be apparent hereinafter. In the accompanying drawings:

Fig. 1 is a part sectional elevation of one head or unit of a glass forming machine showing the adaptation of my lock to the sectional bottom of a finishing mold.

Fig. 2 is a detail side elevation of a finishing mold bottom showing my invention applied thereto.

Fig. 3 is a sectional view taken on the line

III-III of Fig. 2, showing the mold bottom lock in operation.

Fig. 4 is a sectional view similar to Fig. 3, showing the lock in inoperative position and the push-up bottom spindle in its low-
ermost position.

Fig. 5 is a detail transverse section taken along the line V-V of Fig. 4.

Fig. 6 is a part sectional elevation showing a modified form of lock, said lock being in an inoperative position.

Fig. 7 is a view similar to Fig. 6 showing the push-up mold bottom locked in its uppermost position.

Fig. 8 is a fragmentary side elevation taken at right angles to the showing in Figs. 6 and 7.

Fig. 9 is a detail view showing the manner in which the lock shown in Figs. 6, 7 and 8 is operated.

Referring to the accompanying drawings, the machine to which the present invention is shown applied, comprises a stationary vertical column 10, a carriage rotatable about the column 10 and including a bottom section 11 mounting the finishing molds 12, and an intermediate section 13 having suitable operating connections with a turnover unit including a neck mold 14. A blank mold 15 is arranged above and periodically coacts with the neck mold 14 and is adapted to receive charges of glass through its open upper end from any suitable source of supply (not shown) by way of a funnel guide 16 located above the intermediate section 13. After a charge of glass has been delivered to the blank mold, the funnel guide 16 is shifted laterally so that a blowing head 17 may be brought into operative position over the upper end of said blank mold. Upon completing the blank formation, the turnover unit is revolved about its horizontal axis 18 to swing a bare parison or blank (not shown) from the blank mold to a pendent position in which it is enclosed by the finishing mold sections 12 for blowing to the final form of the article being produced. Following blowing of the article in the finishing mold 12, the finishing mold sections separate at a predetermined station and suitable cam mechanism operates to tilt the finishing mold bottom to thereby eject the completed article from the machine. It is understood that a forming machine of the character illustrated, comprises an annular series of units such

100 sections 12 for blowing to the final form of the article being produced. Following blowing of the article in the finishing mold 12, the finishing mold sections separate at a pre-determined station and suitable cam mechanism 105 operates to tilt the finishing mold bottom to thereby eject the completed article from the machine. It is understood that a forming machine of the character illustrated, comprises an annular series of units such

as that shown in Fig. 1 and that the carriage supporting these units rotates continuously about the stationary central column 10, successively bringing the molds to the various operating stations. Preferably, continuous rotation of the carriage is effected by providing said carriage with an annular gear 19 with which a driving pinion 20 meshes, said pinion receiving its power from any suitable source.

The finishing mold bottom comprises a body portion 25 of cup-like formation including a depending tubular guide or sleeve 26. The body portion is journaled in horizontally aligned bearings 27 located inwardly from the vertical center of the mold bottom which is adapted to be tilted outwardly about said bearings 27 at a predetermined station to discharge a completed article. For this purpose, an angular supporting arm 28 is provided and includes a normally pendent portion 29 mounting a cam roll 30 which normally contacts with a vertically movable cam 31. This cam 31 is caused to move periodically relative to the machine proper by a cam track 32. With lifting of the cam 31, the normally pendent portion 29 of the angular arm 28 swings inwardly about the axis of the bearings 27, causing the other portion 33 of the angular arm 28 to tilt downwardly and transmit to the finishing mold bottom a corresponding degree of tilting movement so that the finished article will be thereby ejected. An adjusting screw 22 carried by the horizontal portion 33 of the angular arm 28 permits changing of the angular relation between the mold bottom and said arm.

Arranged within the cup-like body portion 25 of the mold bottom, is an annular section 35 having a portion projecting upwardly and provided with an annular rib 36 adapted to snugly fit into recesses formed in the inner faces of the finishing mold sections 12 when the mold is closed. A plunger section 37, which, in this instance, is shaped to form a re-entrant bottom in the ware being produced, is slidably arranged within the annular section 35 and formed with a depending spindle 38 extending into the guide 26 formed on the lower end of the cup-like body portion 25 of the mold bottom. The lower end of the spindle 38 carries a depending threaded stem 39 having threaded engagement with an adjusting ring or collar 40, said ring provided with an external annular groove 41 adapted at times to receive a locking detent 47 as will be pointed out hereinafter. By rotating the externally grooved adjusting collar 40, the plunger section 37 of the mold bottom may be raised or lowered so that the meeting upper surfaces of said plunger section and the annular section 35 of the mold bottom may be aligned with each other. A spring pressed detent 42 carried

by the spindle 38 may project into any one of an annular series of recesses 23 and serves to lock the spindle 38 and the adjusting collar 40 against accidental relative movement, to thereby permit any setting desired.

The adjusting collar 40 also carries an axially arranged depending stem 43 which is externally screw threaded and has threaded engagement with a shoe 44 which periodically contacts with a stationary cam track 45 for the purpose of transmitting a vertically upward movement to the plunger section of the mold bottom. This shoe 44 is adjustable toward and from the collar 40 and may be locked against accidental relative movement by a spring pressed detent 46, projecting upward into any one of an annular series of recesses 21 (Fig. 5). Axial adjustment of this shoe by rotation, provides means for properly positioning the collar 40 to insure engagement of the main locking detent 47 with the groove in the adjusting collar 40 at proper intervals.

The detent 47 which projects through a radial opening in the tubular guide 26 and into the annular groove 41 formed in the adjusting collar 40, has a pin and slot connection with a bell crank lever 48. This lever 48 is pivoted between ears 49 formed on the tubular guide 26 and has one arm 50 pivoted to a connector 51 slidable vertically in spaced guides 52 and carrying at the upper end a roller 53 adapted at times to be engaged by an inclined cam face 54 formed on one of the finishing mold section carriers 55. This connector 51 preferably comprises a short stem or rod 56 whose upper end extends into a sleeve 57, said sleeve being slidable in the upper guide 52. A coil spring 58 bears against the end of the stem 56 which extends into the sleeve and exerts a downward pressure on said stem to thereby maintain the connector at its maximum length. A second coil spring 59 surrounds the stem 56, and has one end bearing against the lower rod guide 52, while its upper end engages the adjacent end of the sleeve 57. This spring serves to yieldably hold the sleeve and cam roll 53 in their uppermost positions in which the roll may be readily engaged by the inclined cam 54 of the mold sections carrier 55 when the mold closes.

In operation, a formed parison is transferred from the blank mold 15 to the finishing mold sections 12 for final blowing. As the finishing mold sections 12 move toward each other to the closed position (Fig. 3), the inclined cam 54 of the mold section carrier 55, engages the roller 53, causing downward movement of the latter, together with the connector 51, and consequent rocking of the bell crank lever 48 to move the detent 47 inwardly. Just prior to this rocking of the bell crank lever 48, the stationary cam track 45 has caused upward movement of the spindle 38 to a position

in which the upper faces of the plunger section 37 and the annular section 35 of the mold bottom (Fig. 3) are properly aligned. Because of previous adjustment of the collar 40 and the shoe 44, this upward movement of the plunger section 37 in the annular section 35 brings the adjusting collar to a position in which the annular groove or channel 41 of said collar will receive the inner end of the locking detent 47 upon rocking of the bell crank lever 48 as above stated. At a predetermined station, the stationary cam track 45 is formed with a downward dip (not shown). As the finishing mold approaches said downwardly dipped portion of the stationary cam track 45, the mold sections begin to open under influence of well known means (not shown) and thereby disengage the inclined cam on the finishing mold section carrier 55 from the roller 53. This permits the spring 59, surrounding the rod 56, to expand, thereby rocking the bell crank lever 48 and causing retraction of the detent 47 so that the spindle 38 and plunger section 37 may drop away from the article being blown. Immediately following lowering of the plunger section 37, cam mechanism heretofore referred to, and including the vertically movable cam 31 (Fig. 2), operates to tilt the mold bottom causing ejection of the ware at a predetermined station. Thus, during the final blowing of an article, the mold bottom sections are held against relative movement so that "checks", etc., are not formed on the ware bottoms.

In another form of the invention (Figs. 6 to 9, inclusive), the detent 47 is slidable through a radial opening 65 in the guide 26 and is pivoted at its outer end to the upper end of an arm 66 which carries a laterally directed counterweight 67 at its lower end. This arm 66 is pivoted at a supporting bracket 68 substantially at its point of connection to the counterweight so that said counterweight when free to function, drops downwardly causing inward movement of the detent 47 to a locking position (Figs. 7 and 9). Vertical movement of the plunger section 37 within the annular section 35 of the mold bottom is effected by engagement of the shoe 44 with a continuous stationary cam track 69, said cam track 69 being formed with a raised section 70 (Fig. 9) in proximity to the station at which the finishing mold 12 closes around a parison to be blown. During the period of time that the finishing mold is located substantially over the raised portion 70 of the cam track, it is necessary that the locking detent 47 be engaged in the annular groove 41 of the plunger adjusting collar 40. Consequently, the counterweight supporting cam track 71 terminates substantially at the opposite ends of this raised portion 70 of the cam track so that the counterweight 67 may drop downwardly to rock the arm 66 and

project the detent 47 into the groove 41 in the adjusting collar 40.

Because of the fact that contact between the shoe 44 and the frequently irregularly formed cam track 69 frequently causes vertical reciprocation of the plunger section 37 with objectionable results as pointed out, the raised portion 70 of the cam track is formed with a hump 72 at one end, said hump serving initially to elevate the plunger sufficiently to align the annular groove 41 of the adjusting collar 40 with said detent 47 allowing interlocking of the mold bottom sections. This cam track, beyond the hump 72, is sufficiently spaced below the shoe 44 to insure against contact therebetween and thereby prevent any tendency the cam track would have ordinarily to force the plunger 37 upwardly against the locking action on the detent 47. The advantages are obvious. By changing the points at which the ends of the counterweight operating cam track 71 terminate and changing to a greater or less degree the length of the raised portion 70 of the plunger operating cam track 69, raising and lowering of the plunger section 37 of the mold bottom may be properly timed with opening and closing of the finishing molds and tilting of the mold bottom section.

Manifestly, certain minor changes may be resorted to within the spirit and scope of the appended claims.

What I claim is:

1. A glass forming mold comprising a body portion, a mold bottom including an annular section and a vertically movable plunger section in said annular section, and means automatically operable at predetermined time intervals to interlock the mold bottom sections.

2. A glass forming mold comprising a body portion, a mold bottom including an annular section and a vertically movable plunger section in said annular section, means causing proper relative positioning of the mold bottom sections, and means operating automatically to interlock said sections after said proper positioning.

3. A glass forming mold comprising a body portion, a mold bottom including an annular section and a vertically movable plunger section in said annular section, means automatically operable at predetermined time intervals to interlock the mold bottom sections, and means operating at a predetermined period to release said plunger section for downward movement within the annular section.

4. A glass forming mold comprising a body portion, a mold bottom including an annular section and a vertically movable plunger section in said annular section, means causing proper relative positioning of the mold bottom sections, means operating automatically to interlock said sections after said proper positioning, and means operating at a predetermined station to release said plunger section

for downward movement in the annular section:

5. A glass forming mold comprising a body portion, a mold bottom including an annular section and a vertically movable plunger section 70
5 slideable through said annular section, and means operating automatically to interlock the mold bottom sections and later to release the plunger section for downward movement 10 in the annular section.

6. In combination, a continuously rotating mold carriage, a forming mold on said carriage, a tiltable mold bottom for said forming mold including an annular section and a vertically movable plunger section slideable within 75
15 said annular section, a stationary cam track formed to move the plunger section vertically at a predetermined station, and means operating automatically to interlock said mold sections at a predetermined station.

7. In combination, a continuously rotating mold carriage, a forming mold on said carriage, a tiltable mold bottom for said forming mold including an annular section and a vertically movable plunger section slideable within 80
25 said annular section, a stationary cam track formed to move the plunger section vertically at a predetermined station, means operating automatically to interlock said mold sections at a predetermined station, and cam mechanism operating to release the plunger section for downward vertical movement at a succeeding station.

8. In combination, a continuously rotating mold carriage, a forming mold on said carriage, a tiltable mold bottom for said forming mold including an annular section and a vertically movable plunger section slideable within 85
35 said annular section, a stationary cam track formed to move the plunger section vertically upward at a predetermined station, means operating automatically to interlock said mold bottom sections at a predetermined station, and adjustable means for controlling 40
45 the relation between said sections during the period of interlocking engagement between said sections.

9. In combination, a continuously rotating mold carriage, a forming mold on said carriage, a tiltable mold bottom for said forming mold including an annular section and a vertically movable plunger section slideable within 90
50 said annular section, a stationary cam track formed to move the plunger section vertically upward at a predetermined station, means operating automatically to interlock said mold sections at a predetermined station, and adjustable means for varying the degree 95
55 of movement of the plunger section under influence of said cam.

10. The combination of a continuously rotating mold carriage, a forming mold thereon including mold halves movable toward and from each other to close and open the 100
60 mold; a mold bottom including an annular

section and a vertically movable plunger section in said annular section, and means actuated by movement of the mold halves toward each other to interlock the mold bottom sections.

11. The combination of a continuously rotating mold carriage, a forming mold thereon including mold halves movable toward and from each other to close and open the mold; a mold bottom including an annular section 75
70 and a vertically movable plunger section in said annular section, a sliding detent for interlocking the two mold sections, and means actuated by movement of the mold halves toward each other to move the detent to locking position.

12. A glass forming mold comprising a pair of mold halves movable toward and from each other to close and open the mold, a mold bottom including relatively movable 85
80 sections, and a sliding detent carried by one section and movable at intervals to interlock said sections.

13. A glass forming mold comprising a pair of mold halves movable toward and from each other to alternately close and open the mold, a mold bottom including relatively movable sections, means to lock the sections against relative movement, and a cam operable by movement of one of the mold halves 90
95 to operatively position the locking means.

14. A glass forming mold comprising a body portion, a mold bottom including relatively movable sections, means carried by one section and operable to interlock said sections, and means carried by the mold body 100
100 controlling operation of the locking means.

15. A glass forming mold comprising a body portion, a mold bottom including relatively movable sections, means carried by one section and operable to interlock said sections, means carried by the mold body controlling operation of the locking means, and adjusting means to change the degree of movement between said sections. 110

16. A glass forming mold comprising a pair of mold halves movable toward and from each other to close and open the mold, a mold bottom including relatively movable sections, a sliding detent carried by one section, a cam formed on one of the mold halves, and yieldable devices connected to said detent and operable by the cam to cause interlocking of the mold bottom sections. 115

17. Glass forming apparatus comprising, 120
in combination, a continuously rotating mold carriage, a partible mold thereon, a mold bottom comprising telescoping sections, cam mechanism operable to periodically cause relative movement of the mold bottom sections, 125
125 and automatic means interlocking the sections at predetermined intervals.

18. In combination, a continuously rotating mold carriage, a partible mold thereon, a mold bottom including a movable plunger 130

- section, an annular section around said plunger, a spindle depending from said plunger section, a guide for the spindle, a shoe fixed to the lower end of the spindle and 5 adjustable to vary the spacing between the plunger section of the mold bottom and said cam, and means operating automatically to interlock the mold bottom sections at predetermined intervals.
- 10 19. In combination, a mold including a body portion, a mold bottom comprising an annular section, a vertically movable plunger section in said annular section, a spindle depending from the plunger section, a stationary 15 guide for said spindle, a shoe located below said spindle, an adjustable connector interconnecting the shoe and spindle and operable to vary the spacing between said shoe and spindle, means engaging the shoe and 20 formed to transmit an upward movement to the plunger section and spindle at times, and means operating automatically to interlock the spindle guide and said connector when the plunger section reaches its uppermost 25 limit.
20. In combination, a mold including a body portion, a mold bottom comprising an annular section, a vertically movable plunger section in said annular section, a spindle 30 depending from the plunger section, a stationary guide for said spindle, a shoe located below said spindle, an adjustable connector interconnecting the shoe and spindle and operable to vary the spacing between said 35 shoe and spindle, means engaging the shoe and formed to transmit an upward movement to the plunger section and spindle at times, a detent 40 slidable through said spindle guide and adapted to engage the connector to interlock the mold sections, cam means operating to periodically move the plunger section vertically upward, and automatic means for alternately reciprocating said detent in 45 timed relation with vertical movement of the plunger section.
21. In combination, a tiltable mold bottom comprising a supporting member and tubular guide depending from said member, an annular section supported on said member, a 50 plunger section slidable in the stationary annular section, a spindle carried by the plunger section and extending into said guide, a shoe arranged below the guide, a connector 55 interconnecting the shoe and spindle, means operable to lock said connector against longitudinal movement in the guide, said connector being rotatable to vary the relative positions of the annular section and the plunger section, and means adapted to engage said shoe to periodically move the 60 plunger section to its uppermost position.
22. In combination, a tiltable mold bottom comprising a supporting member and tubular guide depending from said member, an annular section supported on said member, a 65 plunger section slidable in the annular section, a spindle carried by the plunger section and extending into said guide, a shoe arranged below the guide, a connector interconnecting the shoe and spindle, means operable to lock said connector against longitudinal movement in the guide, said connector being rotatable to vary the relative 70 positions of the annular section and the plunger section, a stationary cam track formed to 75 engage the shoe and periodically move the plunger section to its uppermost position, and means operating automatically to release the connector at predetermined 80 intervals.
23. A tiltable mold bottom comprising an annular section, a plunger section slidable within the annular section, and means operable at times to interlock said sections including a sliding detent, and a cam to actuate the detent. 85
24. A tiltable mold bottom comprising an annular section, a plunger section slidable within the annular section, a detent for interlocking said sections, a pivoted arm connected to said detent, and a means to rock the arm at intervals causing movement of the detent into locking position. 90
25. A mold bottom comprising an annular section, a plunger section movable in the 95 annular section, a stationary cam track formed to move said plunger section vertically at a predetermined station, a detent carried by the annular section, and cam actuated mechanism causing movement of the detent into and out of locking engagement with the plunger section. 100

Signed at Toledo, in the county of Lucas and State of Ohio, this 23rd day of February, 1927.

ALBERT N. CRAMER.
